[57] CLAIM

The ornamental design for an automatic feeder for fish or birds, as shown and described.

DESCRIPTION

FIG. 1 is a front, top and side perspective view of an automatic feeder for fish or birds, showing my new design, with the cover in open position;

FIG. 2 is a front elevational view thereof;

FIG. 3 is a rear elevational view thereof;

FIG. 4 is a side elevational view thereof from the left of FIG. 2;

FIG. 5 is a side elevational view thereof from the right of FIG. 2;

FIG. 6 is a top plan view thereof; and,

FIG. 7 is a bottom plan view thereof.
